UNITED STATES PATENT OFFICE.

GENNARO ERRICO, OF WATERBURY, CONNECTICUT.

FLY-PAPER HOLDER.

1,103,950.

Specification of Letters Patent. Patented July 21, 1914.

Application filed September 20, 1913. Serial No. 790,896.

To all whom it may concern:

Be it known that I, GENNARO ERRICO, a subject of the King of Italy, residing at Waterbury, in the county of New Haven and State of Connecticut, have invented certain new and useful Improvements in Fly-Paper Holders, of which the following is a specification, reference being had therein to the accompanying drawing.

10 This invention relates to a fly paper holder, and has for its object the production of a holder which is adapted to be positioned upon the outer edges of a piece of fly paper for holding the same upon a support.

15 Another object of the invention is the production of a fly paper holder having a simple locking means for holding the device in engagement with the paper.

20 With the above and other objects in view this invention consists of certain novel combinations, constructions, and arrangements of parts as will be hereinafter fully described and claimed.

25 In the accompanying drawing:—Figure 1 is a top plan view of the device showing the same positioned in engagement with a piece of fly paper. Fig. 2 is a fragmentary perspective view of the locking means. Fig. 3 is a section taken on line 3—3, of Fig. 1 looking in the direction of the arrow. Fig. 4 is a section taken on line 4—4, of Fig. 1 looking in the direction of the arrow. Fig. 5 is a section taken on line 35 5—5, of Fig. 1 looking in the direction of the arrow. Fig. 6 is a perspective view of a portion of one of the retaining strips. Fig. 7 is a fragmentary perspective of one of the retaining strips showing the pivot 40 means formed thereon. Fig. 8 is a plan view of the blank from which the auxiliary locking member is formed. Fig. 9 is a plan view of the blank from which the primary locking strip is formed.

45 Referring to the accompanying drawing by numerals 1 and 2 designate the side strips and 3 and 4 the end strips which are adapted to be positioned upon the edge of a sheet of fly paper. Each of these strips 50 are formed from a blank and are bent so as to constitute a substantially U-shape body in cross section. Since the body is formed as above described it may easily be fitted upon the edge of a fly paper for holding the same in position upon a support as illustrated in dotted lines in Fig. 1. In this

manner it will be seen that the fly paper will be prevented from being blown or otherwise accidentally removed from the support. The end 3 and one corner of the 60 end 4 are provided with the extending lip 5 having an opening 6 formed therein. The side 1 is provided at each end while the side 2 is provided at one end with an overhanging portion 7 which supports the U-shape 65 spacing member 8. This U-shape spacing member 8 and the overhanging portion 7 are provided with the registering apertures 9 which are positioned in alinement with the opening 6 formed in the lip 5. A pivot 70 member or pin 10 is passed through the opening 6 and apertures 9 for holding the end portions of each strip in pivotal engagement with each other. Since the lip 5 and overhanging portion 7 extend beyond 75 the U-shape body of each strip it is necessary to use the U-shape spacing member for holding the corner portions of each strip at a spaced distance from each other for allowing the reception of a sheet of fly 80 paper 11.

After the four strips have been placed in engagement with the edges of a sheet of fly paper it is necessary to lock the free ends of the strips together. In order to accomplish this result the end 4 or principal strip is provided with the spring jaws 12 and 13. The spring jaw 13 extends upwardly and terminates in a rolled sleeve 14. The auxiliary strip or side 2 is provided with a 90 spring tongue 15 which is bent backwardly upon itself so as to terminate in the rolled portion 16. By forcing the end of the side 2 into the spring jaws 12 and 13, the tongue 15 and rolled portion 16 will pass under the 95 rolled sleeve of the jaw 13. The tongue 15 will then spring upwardly while the jaw 13 will spring downwardly so as to allow the rolled portion 16 to rest beyond the sleeve 14. In this manner it will be seen that the 100 side 2 will be prevented from accidentally moving from engagement with the spring jaws 12 and 13.

In order to prevent the strip 2 from moving sidewise from engagement with the 105 spring jaws 12 and 13 there is provided a side sleeve 17 formed integral upon the side 2 and at right angles to the rolled portion 16 of the tongue 15. When the rolled portion 16 rests behind the sleeve 14 the side 110 sleeve 17 will bear upon the reduced side 18 of the jaw 13 while the inner end of the

side sleeve 17 will rest between the spring jaws 12 and 13 as illustrated in Fig. 2. It will, of course, be understood that the side 5 will be prevented from swinging inwardly and out of engagement with the spring jaws 12 and 13 since the fly paper 11 will fit within the U-shape body and prevent the inward movement of the strips.

From the foregoing description it will be 10 seen that a simple and efficient fly paper holder has been produced which may be easily placed upon the edges of a sheet of fly paper and which is provided with a plurality of rolled portions for efficiently locking the free ends of the strip in engagement 15 with each other.

Having thus described the invention what is claimed as new, is:—

1. A fly paper holder comprising a plurality of pivotally secured strips, each strip 20 formed to constitute a U-shape body in cross section, said body adapted to fit upon the edges of a sheet of fly paper for holding the same in position, one of said strips provided 25 at one end with a pair of spring jaws, one of said jaws being positioned above the other, the upper jaw terminating in a rolled sleeve, another of said strips provided with a tongue bent backwardly upon itself and terminating 30 in a rolled portion, the end portion of said last mentioned strip adapted to be positioned between the spring jaws of said first mentioned strip, said rolled portion and said tongue of said last mentioned strip 35 adapted to be positioned within said spring jaws of said first mentioned strip, and said rolled portion of said last mentioned strip adapted to rest behind the rolled sleeve of said spring jaw for holding said strips in 40 engagement with each other.

2. A fly paper holder comprising a plurality of strips adapted to fit upon the edges of a sheet of fly paper, one of said strips provided at one end with a plurality of spring jaws, one of said spring jaws terminating in a rolled sleeve, another of said strips provided with a tongue bent backwardly upon itself and terminating in a rolled portion, a side sleeve formed integral upon one side of said last-mentioned strip 45 at right angles to the rolled portion of said tongue, said tongue and rolled portion of said last-mentioned strip fitting between said spring jaws, said side sleeve of said last-mentioned strip resting against the 50 inner edge of one of said spring jaws for holding the straight ends of said strips in engagement with each other.

3. A fly paper holder comprising a plurality of U-shape strips, said strips provided 60 at their end portions with a plurality of overhanging lips, said lips adapted to be pivotally secured to each other for holding the strips in pivotal engagement, a U- 65 shape spacing member positioned between said overhanging lips for holding the same in spaced relation, a pivot member passing through a plurality of said lips and one of said spacing members for holding the strips in pivotal engagement, and means carried 70 by one of the corners formed by a plurality of said strips for holding the free ends in detachable locked engagement.

In testimony whereof I hereunto affix my signature in presence of two witnesses.

GENNARO ERRICO.
